UNITED STATES PATENT OFFICE.

PIUS O. TOGNELLI, OF LINCOLN, CALIFORNIA.

DESIGN FOR AN INTERNATIONAL PATRIOTIC EMBLEM.

53,720.

Specification for Design.

Patented Aug. 19, 1919.

Application filed October 24, 1918. Serial No. 259,592. Term of patent 3½ years.

To all whom it may concern:

Be it known that I, Pius O. Tognelli, a citizen of the United States, residing at Lincoln, in the county of Placer, State of California, have invented a new, original, and Ornamental Design for International Patriotic Emblems, of which the following is a specification, reference being had to the accompanying drawings, forming part thereof.

Fig. 2 is a rear view, showing the design.

I claim:

The ornamental design for an international patriotic emblem, as shown.

PIUS O. TOGNELLI.
